COKE-OVEN

James McIntosh, Pittsburgh, Pa., assignor to
 Carnegie Steel Company, Pittsburgh, Pa., a
 corporation of New Jersey

Application March 21, 1933, Serial No. 661,961

1 Claim. (Cl. 202—263)

This invention relates in general to coking plants, and has more particular reference to the provision of effective means for taking care of the smoke incident to the charging or recharging of a heated coking oven.

In the operation of by-product coke-ovens each charge, as completely coked, is pushed from the coking chamber or oven and a succeeding charge is deposited therein immediately.

10 There is, of course, a high temperature in the oven chamber and as the coal is poured into the oven considerable smoke and gases are evolved, which are commonly discharged directly from the charging or recharging holes and ascension pipes of the ovens into the open air.

This invention has for one of its objects the by-passing of the escaping gas and smoke from the oven being charged into one of the adjacent ovens and thence into the collector main, therefore 20 by eliminating the pollution of the atmosphere, the loss of by-products, the damage to the charging car and the hazard to the operators.

Another object is the provision of a novel mechanism (to be described in detail) for connecting the oven to be charged to an adjacent oven.

A further object is to provide a novel control for the charging car which will prevent the operation of the car while it is operatively associated with the ovens.

30 In the drawings:

Figure 1 is a plan view of several ovens of a battery of coke-ovens with the charging mechanism in position.

35 Figure 2 is a sectional view taken on the line II—II of Figure 1.

Figure 3 is a sectional elevation through a battery of ovens showing the charging car mechanism in end elevation.

40 Figure 4 is a sectional elevation through the charging car and by-pass conduit.

Figure 5 is a sectional view taken on the line V—V of Figure 1.

Referring more particularly to the drawings 45 which show the apparatus of my invention associated with a standard form of by-product oven, the letter A designates a battery of ovens which are provided with the usual charging and recharging openings or holes 2 closed by lids 1. The oven to be charged is designated by the numeral 3 while the adjacent oven to which the smoke is evolved from the oven being charged is by-passed is designated by the numeral 5. A loaded electrically propelled charging larry car 50 is shown in position with its hopper spouts 6

directly above the charging holes 2 of the oven 3 to be charged. The larry car is provided with a plurality of charging hoppers equal in number to the number of charging holes in each oven of the battery, and each of the hoppers is provided with one of the spouts 6. Each hopper spout 6 is provided with a vertically movable drop sleeve 9 adapted to be lowered so as to connect the hopper spouts with the charging holes 2 of the oven to be charged.

The hopper spout of the charging larry car nearest the coke discharge end of the ovens is connected to a by-pass conduit 8 of such length that it will bridge the distance between the spout and one of the charging holes of the next adjacent oven. The conduit 8 is provided at its free end with a vertically movable drop sleeve 7 adapted to be lowered and connected with one of the charging openings or holes of the oven adjacent the oven being charged. The four drop sleeves 9 on the larry car hopper spout 6 and the single drop sleeve 7 on the by-pass duct 8 are all adapted to be simultaneously lowered by the larry car operator from his cab. The lowering of the drop sleeves 9 is accomplished by a lever 10, links 11, line-shaft 12, levers 13 and links 14. The drop sleeve 7 on the discharging end of the by-pass duct or conduit 8 is adapted to be lowered at the same time as the sleeves 9 by means of a lever 15 and cable 16 trained over pulleys 17. The levers 13 of the operating mechanism for the sleeves 9 are equipped with counterweights 18 which partially counterbalance the weight of the sleeves and effect easier operation in raising them.

35 The electrically propelled larry car is provided with an operating motor 19 which includes in its circuit a main circuit-breaker 20 of any usual construction, and this circuit-breaker is connected to the operating lever 10 of the sleeve-operating mechanism by links 21 in such manner that the circuit to the motor 19 is broken when the drop sleeves 7 and 9 are lowered by the mechanism described above.

After the drop sleeves 7 and 9 are lowered 45 the cut-off gates 22 in each of the hoppers of the larry charging car are individually opened by the operator through levers 23, links 24 and 25 and shafts 26, and the coal from the larry car hoppers is permitted to drop by gravity 50 into the oven 3 being charged. The lever and link operating mechanism for the cut-off gates 22 is so adjusted that the gates of the end hoppers are opened ten seconds or more before those of the center hoppers so as to permit the coal being 55

charged to run clear of the brickwork around the charging holes at the ends of the oven, causing any excess in the amount of coal charged to remain in the charging holes at the middle of the oven. This method of charging leaves a gas pocket above the top of the coal at each end of the oven for the excess coal piled up at the middle of the oven. The inlet end of the by-pass conduit or duct 8, that is the end connected with 5 and communicating with the hopper spout nearest the coke discharging end of the ovens, is equipped with a counterweighted valve or gate 28 which when closed is adapted to prevent coal and dust entering the conduit or duct 8 from 10 the hopper spout during the charging operation. The gate 28 when in open position extends into the path of travel of the coal through the hopper spout and the passage of the coal through said spout is adapted to operate or move the gate into 15 closed position. The valve or gate 28 has an operating shaft 28^a and a counterweight 38 mounted on a lever 28^b.

The conduit or duct 8 is provided at its entrance end, which is the end connected with the 25 hopper spout, with a trap pocket 8^a adapted to receive and trap any coal or dust which may enter the conduit past the valve or gate 28. The pocket 8^a is provided with a counterweighted closure 8^b which may be opened to permit the 30 discharge of any of the trapped material.

Substantially simultaneously with the opening of the gates 21, to permit the coal being charged to flow to the oven, valves 29 will be opened to permit steam to flow to aspirator nozzles 30 35 located in ascension pipes 31 of the ovens 3 and 5. The steam from the aspirator nozzles 30 induces a suction in the pusher end of the oven 3 which is being charged and through the gas passage 32 of the adjacent oven 5 to which the 40 conduit 8 delivers its smoke and gases. The suction created in the oven 5 is effected through the by-pass conduit or duct 8 and in the coke delivery end of the oven 3 being charged. This 45 suction pulls all of the gas, smoke and vapor from the oven 3 into the ascension pipe and thence into the collector main 33.

After the coal has been charged in the oven 3 the cut-off gates 21 are closed by the operator so as to prevent the escape of smoke and gases 50 through the hoppers of the charging car. The oven operators next level the coal in the oven which has been charged, and if an excess of coal has been charged the excess will be withdrawn 55 from the oven so as to leave a clear gas passage along the top of the charged oven.

After the coal has been leveled an operator will raise the drop sleeves 9 of the hoppers, with the exception of the hopper to which the by-pass conduit or duct 8 is connected. The raising of these drop sleeves 9 is done by means of levers 5 34 and links 14 which raise the sleeves a sufficient height to permit replacement of the lids 1. Latches 35 are provided for holding the sleeves in their raised position while the lids 1 are being replaced, and after the lids have been replaced 10 the sleeves 9 are returned to their lowermost position.

After the lids 1 have been replaced, as described above, the operator of the larry car will simultaneously raise all of the drop sleeves 7 15 and 9 to their uppermost positions. As the drop sleeves 7 and 9 are raised to their uppermost positions, the circuit-breaker 18 will be automatically closed to complete the circuit to the larry car operating motor 19. The lids 1 are 20 then replaced on the charging holes at the end of the ovens 3 and 5 through which the smoke and gases have been by-passed, and the steam valves 29 will be closed since the aspirating effect 25 of the steam in the ascension pipes is no longer necessary. After the lids 1 have all been replaced the larry car is moved along the battery of ovens to the cold storage bin and loaded with another charge of coal and the charging operation is 30 repeated for another oven.

I claim:

A coke-oven battery coal-charging larry car carrying a hopper for each of the recharging openings of one oven, means connecting each 35 of said hoppers with one of said charging openings of the oven to be charged, a smoke conduit connected to and communicating with at least one of said first named means and adapted for connection with one of the charging openings of an adjacent oven, a valve in said smoke conduit 40 adjacent its point of communication with said first named means, said valve being operable into closed position by the passage of coal through said first named means, whereby the 45 passage of coal and dust into said smoke conduit is prevented, said smoke conduit being provided with a trap pocket adjacent its end communicating with said first named means to trap any coal and dust passing said valve, said trap pocket being provided with a discharge 50 opening, and a valve in said discharge opening for effecting the discharge of the trapped material.

JAMES McINTOSH.
